UNITED STATES PATENT OFFICE.

WILLIAM GREGG LERCH, OF AKRON, OHIO, ASSIGNOR TO THE MILLER RUBBER COMPANY, A CORPORATION OF OHIO.

METHOD OF AND APPARATUS FOR STRIPPING HOLLOW ARTICLES FROM FORMS OR CORES.

1,330,595.

Specification of Letters Patent. Patented Feb. 10, 1920.

Application filed April 26, 1919. Serial No. 293,010.

To all whom it may concern:

Be it known that I, WILLIAM G. LERCH, a citizen of the United States, and resident of Akron, Ohio, have invented certain new and 5 useful Improvements in Methods of and Apparatus for Stripping Hollow Articles from Forms or Cores, of which the following is a specification.

My present invention relates to an improved method of and apparatus for stripping or removing hollow articles from forms or cores, and more particularly to the stripping of articles made from rubber solutions by the dipping therein of a suitably shaped form or core, such for example as toy balloons.

The invention aims to provide a simple, economical and expeditious process by which the articles may be readily removed from the forms, without damage or injury to the articles and without the necessity of turning them inside out or rolling the material upon itself to effect the removal.

With these and other objects in view the invention includes the novel method and form of apparatus suitable for carrying out the method as hereinafter described and defined by the appended claims.

In order that my invention may be more readily understood, I append hereto a drawing illustrating the manner of carrying out the same, in which—

Figure 1 is a perspective view of my preferred form of apparatus.

Fig. 2 is a plan view illustrating the commencement of the removing operation.

Fig. 3 is a view illustrating a subsequent stage in the operation, and

Fig. 4 is a view of the parts as they appear near the completion of the operation.

Referring by reference characters to this drawing the numeral 1 designates a support to which a form is detachably connected in such a manner as to permit the form bearing the hollow article to be readily placed thereon for stripping the article, and quickly removed and replaced by a fresh form. A convenient form of support is to make the supporting member in the form of a block having a recess 1^a to receive the flanged base 2^a of the form 2, such recess having a narrower slot 1^b in its front wall to fit the portion or shank of the form immediately above the flanged base.

In the embodiment shown the support is 55 designed to coöperate with the forms customarily used for making toy balloons, but when the forms are of different design the support would be modified accordingly.

The forms of toy balloons have a bulb 60 shaped portion 2^b upon which the balloon body 3 is formed, the neck 3^a of the balloon extending part way down the shank. At 4 is shown a pipe adapted to be supplied with fluid under pressure from any convenient 65 source (not shown) such as compressed air, and this pipe is provided with a nozzle 4^a, preferably of flattened form, arranged in proximity to the edge of the article on the form so as to direct a jet of air against the 70 edge of the article.

In carrying out my improved method I place the form bearing the article to be stripped on the support 1 and then grasp the neck of the balloon with the thumb and 75 fore finger as shown in Fig. 2 and pinch or press the same so as to force a portion of the beaded edge of the neck away from the form to produce a pocket into which the jet of air penetrates from the nozzle. The air 80 thus entering the pocket starts the inflation of the article by penetrating between its inner wall and the form, whereupon I release the neck of the balloon with the left hand, and grasp it in such a manner as to enable 85 the left hand to assist the right hand in maintaining the balloon against too great inflation and cause the balloon to assume a shape for convenient stripping or removal by a longitudinal movement axially of the 90 form, as shown in Fig. 3. This longitudinal movement is continued until the beaded portion of the neck of the balloon contacts with the bulb portion of the form whereupon the longitudinal pull is continued and the body 95 of the balloon simultaneously squeezed which forces the entrapped air out between the beaded portion of the balloon and bulb of the form, enabling the completion of the removal in a safe and easy manner, as shown 100 in Fig. 4.

Having thus described my invention what I claim is—

1. The hereindescribed method of stripping hollow flexible articles having relatively large bodies and small necks from forms or cores which consists in displacing a portion of the edge of the neck of the arti-

cle from the form, injecting a stationary jet of fluid into the space so formed, and thereafter stripping the article from the form.

2. Apparatus for removing hollow articles having relatively large bodies and small necks from their forms or cores comprising a stationary support having means for detachably and interchangeably holding the forms, and a fixed pipe for compressed fluid 10 having a jet nozzle in proximity to a portion of the form when so held.

3. Apparatus for removing toy balloons from forms having flanged shanks comprising a stationary member having an open slot 15 to receive the stem and an enlarged portion to receive the flange, and a nozzle for directing a jet of fluid under pressure against the stem when so held.

4. The hereindescribed method of remov-

ing toy balloons from their forms or cores, 20 which consists in expanding the balloon by fluid pressure introduced between the neck of the balloon and the form, withdrawing the balloon until its mouth contacts with the bulb portion of the form, and simultaneously squeezing the balloon to expel entrapped air and simultaneously completing its withdrawal.

5. The hereindescribed method of removing expansible articles having relatively 30 large bodies and small necks from their forms or cores which consists in expanding the articles by fluid pressure, while grasping the article so as to prevent over inflation, and withdrawing the article while so 35 expanded.

In testimony whereof, I affix my signature.

WILLIAM GREGG LERCH.
